UNITED STATES PATENT OFFICE.

STELLA SHAULE JOHNSON, OF DENVER, COLORADO, ASSIGNOR OF ONE-HALF TO ELLA LOUISE ANDREWS, OF DENVER, COLORADO.

DESIGN FOR A STATUETTE OR SIMILAR ARTICLE.

Application filed June 23, 1924. Serial No. 9,951. Term of patent 3½ years.

To all whom it may concern:

Be it known that I, STELLA SHAULE JOHNSON, a citizen of the United States, residing in the city and county of Denver, State of Colorado, have invented a new, original, and ornamental Design for a Statuette or Similar Article, of which the following is a specification, reference being had to the accompanying drawing, forming a part thereof.

In the drawing, Figure 1 is a front elevational view of a statuette embodying my new, original and ornamental design, Figure 2 is a side elevational view thereof, and Figure 3 is a rear elevational view of the same.

I claim:—

The ornamental design for a statuette or similar article as shown.

In testimony whereof, I affix my signature.

STELLA SHAULE JOHNSON.
